ROBERT S. CURLEY, OF LOWELL, MASSACHUSETTS, ASSIGNOR TO SACO-LOWELL SHOPS, OF NEWTON UPPER FALLS, MASSACHUSETTS, A CORPORATION OF MASSACHUSETTS

COTTON WORKING METHOD AND MACHINE

Application filed May 16, 1929. Serial No. 363,586.

This invention relates to methods and machines used to prepare cotton for carding. The invention is especially concerned with those systems which take loose cotton and work it into a finished lap in a single process and which are commonly referred to commercially as "single process picker systems".

In the past such systems have been used in this country only to a very limited extent, but due to recent developments they are now going into use very rapidly. The chief difficulty encountered in operating a system of this character resides in the fact that there are necessarily very wide variations in the initial rate of delivery of cotton to the system, and these variations must be eliminated as the cotton passes through the system in order to produce a lap having that degree of evenness or yard for yard uniformity which is necessary for carding. It is the chief object of the present invention, therefore, to compensate for the variations in the delivery of cotton to a picking mechanism, to smooth out and reduce such variations, to reduce the skill required in handling such systems, and to deliver a substantially uniform web of cotton at the discharge end of the machine or system.

The nature of the invention will be readily understood from the following description when read in connection with the accompanying drawings, and the novel features will be particularly pointed out in the appended claims.

In the drawings,

Figure 1 is a vertical sectional view, somewhat diagrammatic, of a single process picker system embodying features of this invention;

Figs. 2 and 3 are side views on a larger scale of said system, approximately one-half of the system being shown in each view;

Fig. 4 is an elevation of part of the first feed hopper in the system showing parts of the conveying system that supplies cotton to the picking machines; and

Fig. 5 is a plan view showing certain parts of the control mechanism indicated in elevation in Fig. 2.

In either the single process picker systems

or the older systems, it is the usual custom to prepare the cotton for delivery to the picker room by passing it through a series of opening and cleaning operations. In a typical arrangement the cotton is delivered from the bales to the bale breaker and discharged from the bale breaker into a vertical opener, thence into a lattice opener or horizontal cleaner, and finally is conveyed pneumatically to the picker room. A single set of opening and cleaning machinery will supply several pickers, and it is the usual practice, therefore, to deliver the cotton to the feed hoppers of the several picking machines by a Morton distributor. The system shown in the drawings includes a hopper feeder 2 arranged to receive its supply of cotton from a Morton distributor, the hopper of the feeder being equipped with the usual feeler fork 3 and mechanism automatically controlled thereby for governing the discharge of cotton from the conveyor belt 4, Fig. 4, of the distributor into the hopper. This mechanism is well known in this art and no disclosure of it other than that made in the drawings is necessary. As usual, the arrangement is such that when the supply of cotton in the hopper 2 drops below a level which is roughly predetermined, the feeler fork will be swung forward automatically, thus causing the distributor gate to swing across the conveyor belt 4 and divert cotton into the hopper 2. The increased weight of cotton acting on the feeler fork swings it back to its original position after a time, thus causing the gate to close again and stop the delivery of cotton to the hopper. There are inevitably substantial variations in the quantity of cotton maintained in the hopper 2. These variations are caused partly by the nature of the control mechanism and partly by the fact that when more than one machine calls for cotton at the same time the first machine in the series receives its supply of cotton before any subsequent machine can be supplied. The hopper feeder 2 also includes the usual horizontal feed lattice 5 carrying the cotton forward to an inclined lattice 6 which delivers it to the discharge chute 7.

In the arrangement shown the feeder 2 delivers its cotton on the upper run of a lattice 8 which conveys the cotton to the feed rolls of the first picker unit consisting, in this instance, of a so-called Buckley beater 9 of a well known type. From this machine the cotton is discharged into a condenser section 10 of a common construction and the web of loosely associated fibres delivered by the condenser is fed through feed rolls 12, Fig. 1, into a second or intermediate hopper feeder 14. This feeder is substantially like that shown at 2 and is equipped with the usual horizontal and inclined feed lattices 15 and 16, respectively. The discharge chute 17 of this feeder delivers the cotton to a horizontal lattice 18 which carries it forward through suitable feed rolls and under the roll 19 of an evener mechanism 20, Fig. 20, 3, into the beater 21 of another picker unit consisting of a lapper. The cotton passes from the beater through the screen section 22 and through the usual calendar rolls to the winding rolls 23-23 which wind it up 25 to produce a lap L, Fig. 3.

Any desired number of picker units may be used in this system, and the specific construction of these units will vary with the requirements of different installations and 30 the preferences of individual manufacturers, but for purposes of simplicity only two picking machines are included in the system shown. In its general organization the system illustrated is quite similar to that disclosed in the Rowe application Serial No. 35 248,363, assigned to the assignee of the present invention.

As above indicated, the present invention deals particularly with the feeding of the 40 cotton from one unit to another and with the control of the rate of delivery of cotton to the end that cotton will be delivered at a very uniform rate to the lapper so that the yard for yard variations in weight of cotton 45 in the lap will be reduced to a minimum. It will be observed that in this system the cotton is being advanced continuously from the first hopper feeder 2 to the lapper, this advancing movement being produced partly by devices 50 which perform simply the function of feeding cotton, and partly also by the machines which beat, clean, or otherwise act on the cotton. There are very substantial variations in the rate of delivery of the cotton from 55 the hopper feeder 2, and these variations necessarily continue in the cotton as it is carried through the beater 9 and screen section 10 until it reaches the second or intermediate hopper feeder 14. The hopper of this feeder 60 acts as a reservoir, and due to that fact it tends to smooth out or reduce the variations in the movement of cotton.

It has been found that when a feeder of this type is used to supply cotton to a lapper 65 the laps tend to run heavy when the cotton

in the hopper is maintained at a high level, and that they will run light or thin when the supply of cotton in the hopper is kept at a low level. Apparently this is due to the fact that the pins on the bars of the lattice 16, 70 pick up and carry over more cotton when the hopper is full, or nearly so, than when the level is lower. But whatever may be the cause, it has been demonstrated that if a substantially constant quantity of cotton is 75 maintained in the hopper 14, the feed lattices will deliver cotton from the hopper at a very uniform rate. In the present system, therefore, provision is made for automatically controlling the rate of delivery of the 80 cotton to the hopper 14 in such a manner that a substantially constant quantity will be kept in this hopper at all times.

For this purpose a feeler fork 25 is mounted in the hopper in an inclined position, and is supported on a horizontal rock shaft 26 mounted in the upper part of the hopper. Referring to Fig. 2 it will be seen that a horizontal arm 27 is fastened to the rock shaft 26 and adjustably carries a weight 28, 90 which tends to swing the feeler 25 forward. A link 30 connects the end of the arm 27 with one arm of a bell crank lever 31 fulcrumed at 32 and having an approximately upright arm 33 which is slotted to receive a horizontal rod 34. Two collars 39 adjustable on this rod at opposite sides of the arm 33 permit a suitable adjustment of the arm relatively to the rod. This rod is connected to the controlling element 35 of a variable speed mechanism which drives the elements that feed cotton to the intermediate hopper. Preferably this variable speed mechanism is of the cone pulley type, and the controlling element 35 therefore consists of a belt shifter 100 or belt adjusting device.

As shown in Fig. 2, the variable speed mechanism comprises a driving cone pulley 36 and a driven cone pulley 37 with a belt 38 connecting them, and the belt adjuster or shifter 35 controls the position of the belt on the two pulleys. The driving pulley 36 is itself driven at a substantially constant speed. In the particular arrangement shown this pulley is mounted fast on a horizontal shaft 40 carrying a spur gear 41 meshing with a spiral gear 42 which is located at an angle and is driven by another spur gear 43 fast on a shaft 44. This shaft carries a pulley 45 which is belted to the shaft 46 of the Buckley beater 9, and this shaft, in turn, is driven by a belt 47 from a pulley 48 on the motor stand or driving shaft stand 50.

It will be clear that if the cone pulley 36 is driven at a constant speed by the mechanism just described and the belt shifter or adjuster 35 is moved toward the right, Fig. 2, the driven cone pulley 37 will revolve at a slower speed, while a movement of the belt toward the left will cause the driven pulley 130

to be revolved at a higher speed. The latter pulley is secured fast on a shaft 51 having two worms 52 and 53, respectively, at its opposite ends. The first of these worms drives a worm wheel 54 fast on the shaft 55, and this shaft is geared to all of the feed rolls of the Buckley beater 9 and to a shaft 56 which operates the inclined feed lattice or apron 8. The other worm 53 drives a worm wheel 57 fast on the shaft 58 and this shaft carries a sprocket wheel 60 which is connected by a chain 61 with the shaft 62 for driving the inclined feed lattice 6 in the hopper feeder 2. This inclined lattice and the horizontal lattice 5 are positively connected together in the usual manner.

It will thus be clear that all of the feeding elements between the condenser section 10 and the hopper 2, including the feed lattices in the hopper, are driven from the same source but at variable speeds, and that these speeds are under the control of the belt shifter or adjuster 35. This element 35, in turn, is directly and positively connected with the feeler fork 25 in the intermediate hopper 14 so that any substantial movement of the feeler fork 25 produces a corresponding adjustment of the belt 38 and therefore a change in the operating speed of the elements that feed cotton from the first hopper 2 toward the intermediate hopper 14. The speed of the beater cylinder, the screens in the screen section 10, and the feed rolls 12 between the screen and the intermediate hopper remains substantially constant, but these elements can advance cotton only as fast as it is fed to them. They are incapable of making any change in the rate of delivery of the cotton. Consequently, if cotton is fed to them at a uniform rate they will advance it at a uniform rate. It is, therefore, unnecessary to change their speeds since the rate at which they deliver cotton will be determined entirely by the rate at which the cotton is delivered to them.

The cotton delivered by the condenser screens 10 and feed rolls 12 slides down a stationary apron 64, Fig. 1, behind the feeler fork 25 on to the horizontal apron 15 and under the lower edge of the feeler. It tends to wind up into a loose roll, supported partly by the two lattices or aprons 15 and 16 and partly by the feeler 25, and this body of cotton revolves slowly in contact with the feeler due to the action of the lattices on it. It does not lie in the hopper in a loose substantially stationary mass. This movement of the cotton is of advantage both in producing a more sensitive action of the feeler 25 and also in effecting a more thorough blending of the stock. With this arrangement the feeler responds very quickly to changes in the weight of cotton in the hopper 14 and produces correspondingly quick

changes in the speed of the driven pulley 37 of the variable speed mechanism. The result is that the quantity of cotton in the hopper 14 is maintained substantially constant and this, in turn, causes the hopper 14 to deliver cotton at a very uniform rate to the lapper. While some variations in the weight of cotton in the hopper 14 necessarily will occur, the arrangement is such that these variations will be maintained with very narrow limits.

Between the hopper feeder 14 and the lapper is the evener 20 which operates still further to reduce variations in the delivery of cotton to the lapper. Due to the fact that the variations in cotton coming to it are small, this evener is enabled to operate under particularly favorable conditions, and its own operation is improved. It has been found in actual practice that this system will produce laps even more uniform than those produced by the old "three process system", which heretofore has been regarded as the standard picker system for fine work.

As the cotton is discharged on to the lattices or aprons 8 and 18 from the discharge chutes 7 and 17, respectively, of the two feeders, there is some tendency for it to pile up in a fluffy mass, and in order to avoid this difficulty feed rolls 65 and 66, respectively, have been located to press the cotton down on to the respective lattices or aprons immediately in front of the point at which it comes in contact with the lattices. These rolls are provided with relatively wide ribs and the roll 65 is driven at a slightly higher surface speed than the lattice 8 while the roll 66 is driven at a considerably higher speed, preferably at least twice that of its cooperating lattice 18 and acts to crowd and pack the cotton against the first evener feed roll. This increases the accuracy of the evener mechanism.

When a lap has been completed it is necessary to stop the lapper in order to take out the completed lap and put into the machine the bar or core on which a new lap is to be wound. This stopping operation is performed automatically by the usual knock-off mechanism. It will be clear that when such a shut down occurs the entire feeding movement of cotton from the hopper 2 toward the lapper should be stopped. Also, that when the lapper is again started up the cotton feeding mechanisms should be started simultaneously throughout the entire system.

Referring to Fig. 3 it will be observed that the main shaft 68 of the lapper is driven by a belt connection to the beater shaft 69 which, in turn, is driven at a substantially constant speed from the overhead shaft 70. The driving cone 71 of the evener mechanism 20 is mounted on a horizontal shaft 72 which carries a spur gear 73 meshing with an angular-

ly disposed spiral gear 74 driven from another spur gear 75 fast on the shaft 68.

The shaft of the driven cone 76, Fig. 3, of the evener mechanism 20, carries a worm 18 which drives a worm wheel 77 fast on a shaft 78. This shaft is connected by a driving chain with the shaft 79 which drives the lattice 16 in the intermediate feed hopper 14. The latter lattice is connected with the horizontal lattice 15 in the usual manner. The upper cone shaft also drives a worm wheel on the shaft 85 which, in turn, drives the cotton feeding mechanism between the feeder 14 and the beater 21, said mechanism including the evener rolls. This is a well known arrangement.

The usual knock-off mechanism for the lapper includes a drop bar 80, Fig. 3, which is pivoted or fulcrumed at 81. A rod 82 connects the lower end of this bar or lever with an upright rock shaft 83 having an arm 84 arranged to operate a clutch to start or stop the shaft 85 which drives the cotton feeding rolls associated with the evener 20. The rock shaft 83 also is connected through a link 101 with a clutch operating lever 102 for throwing in or out the clutch which connects the worm wheel 77 with the shaft 78. Another arm projecting from the rock shaft 83 is connected by a link 86, lever 87, and rod 88 to the control lever 89 of a positively operating unit 90 of the character shown in pending application Serial No. 192,910 assigned to the assignee of this invention. This unit 35 or mechanism is driven by a belt connection to the beater shaft 69 of the lapper which runs constantly. Consequently, when the drop bar 80 is released it will operate through the connections just described to bring the mechanism or unit 90 into action. This mechanism includes a slide or traveller 91 which is positively moved by the mechanism toward the right or left, depending upon the direction of actuation of the control lever 89. 40 When the bar 80 drops the slide 91 is moved toward the left, Fig. 3. A rod 92 connects this slide with an upright rock shaft 93, Figs. 2 and 5, and this shaft carries an arm for operating a clutch 94 to start or stop the feed rolls 12. Another rod 95 connects the shaft 93 with a third upright rock shaft 96 carrying an arm 97 for operating a clutch which connects or disconnects the shaft 55 with the worm 54. The lattice or apron 8 and all the 45 feed rolls for feeding cotton from this lattice into the beater of the unit 9 are positively driven from this shaft 55 so that they are stopped when this clutch is thrown out. The rod 98, Fig. 5, connects the rock shaft 97 with a lever 99 for operating the clutch which controls the driving connection between the worm wheel 57 and its shaft 58 for driving the feed lattices in the first hopper 2.

It will be evident, therefore, that the operation of the knock-off mechanism for the lap-

per automatically shuts down all of the feeding mechanisms between the hopper 2 and the lapper, and that when the drop bar 80 is raised again to start the lapper into operation the feed mechanisms will all be started into operation again automatically and substantially simultaneously. While the clutch operating levers 94, 97 and 99 are not directly operated by the drop bar, they are operated indirectly through the positively acting power driven unit 90, and this unit has provision for automatically interrupting its own action whenever it has moved the slide 91 a predetermined distance, either to the right or left.

The invention provides a single process picker system which is superior to prior systems in the quality of the work that it will produce. This has been definitely established in practical operation of the system in many mills. The system is entirely automatic in its action. An especially important practical advantage of this system as compared with prior one-process systems is the fact that it is much easier to control and that any adjustments which must be made while the machine is in operation to compensate for varying conditions are of a very simple nature and entirely within the ability of the usual mill help. The difficulties of control which have proved troublesome in prior systems are practically eliminated. When the system is used in connection with modern opening room equipment such as that above described, no manual handling of the cotton whatever occurs between the time that the cotton is placed in the bale breaker and the removal of the finished lap from the picker system. In addition, as above stated, the system when properly adjusted can be made to produce results superior to those ordinarily obtained by the old three-process picker systems. Some features of the invention also are useful in other relationships than in the particular system illustrated.

While cotton has been designated as the particular fibre handled by the system, since this is the fibre for which the system is designed fundamentally, it is contemplated that the system may be used in the handling of other fibre and the term "cotton", therefore, is intended to include any fibre which the apparatus is capable of handling.

While I have herein shown and described a preferred form of apparatus embodying the invention, it will be understood that this disclosure has been made rather by way of illustration than limitation, and the invention may be embodied in a considerable variety of forms without departing from the spirit or scope thereof. Also, that the method provided by the invention may be practiced with various forms of apparatus.

The claims on subject matter common to this application and my copending appli-

cation Serial No. 224,968, filed October 8, 1927, are presented in the latter case, the claims in the present application being confined to subject matter not disclosed in the 5 earlier case.

Having thus described my invention, what I desire to claim as new is:

1. That improvement in processes of picking cotton and the like, which consists in subjecting the cotton to a plurality of picking operations and finally working it into the form of a lap, feeding the cotton continuously from one operation to the next, feeding the cotton through a reservoir between certain of 10 the picking operations, and constantly controlling the rate of delivery of cotton to said reservoir in response to variations in the supply of cotton in the reservoir.

2. That improvement in processes of picking cotton and the like, which consists in subjecting the cotton to a plurality of picking operations and finally working it into the form of a lap, feeding the cotton continuously from one operation to the next, feeding the 15 cotton through a reservoir between certain of the picking operations, and causing increases or decreases in the supply of cotton in said reservoir to decrease or increase, respectively, the rate of delivery of cotton to said reservoir 20 to maintain variations in the quantity of cotton in said reservoir within very narrow limits.

3. That improvement in processes of picking cotton and the like, which consists in subjecting the cotton to a plurality of picking operations and finally working it into the form of a lap, feeding the cotton continuously from one operation to the next, feeding the cotton through a reservoir between certain of 35 the picking operations, and utilizing variations in the weight of cotton in said reservoir to control the rate of delivery of cotton to said reservoir to maintain said variation within very narrow limits.

4. In an apparatus of the character described, the combination of a hopper feeder, means for feeding cotton continuously to the hopper of said feeder, said means including a picker, variable speed mechanism for driving cotton feeding elements of said means, devices operating automatically through said mechanism to control the operating speed of said cotton feeding elements in accordance with variations in the weight of cotton in said 40 hopper and serving to maintain said variations within very narrow limits, and additional mechanism for automatically starting and stopping said cotton feeding elements in accordance with the demand for cotton fed from said hopper feeder.

5. In a single process picker system, the combination of a series of machines arranged to act successively and continuously on a supply of cotton to work it into the form of a lap, said series of machines including two hopper 45

feeders and a picker between said feeders, a variable speed mechanism for driving the first hopper feeder and the cotton feeding elements of said picker, a feeler responsive automatically to variations in the weight of cotton in the hopper of said second feeder, and connections between said feeler and said variable speed mechanism for causing said mechanism to vary the rate at which said first hopper feeder and said picker will deliver cotton to the second hopper in accordance with variations in the quantity of cotton in said second hopper feeder. 70

6. A single process picker system comprising, in combination, a hopper feeder arranged to receive cotton automatically from a distributing system, mechanism for automatically controlling the delivery of cotton to said feeder in accordance with the requirements of said feeder, a plurality of picker units in series with said hopper feeder and to which the cotton is fed successively from said feeder, one of said units consisting of a lapper, a second hopper feeder between said units and through which the cotton is fed from one of said units to the next, cotton feeding devices between said hopper feeders, variable speed mechanism for driving said feeding devices, and means automatically responsive to variations in the weight of cotton in said second hopper feeder for controlling said variable speed mechanism to cause it to speed up the rate of delivery of cotton to said second hopper feeder when the supply therein decreases and to reduce such rate of delivery when the supply increases. 80

7. A single process picker system comprising, in combination, a hopper feeder arranged to receive cotton automatically from a distributing system, mechanism for automatically controlling the delivery of cotton to said feeder in accordance with the requirements of the feeder, a plurality of picker units in series with said hopper feeder and to which the cotton is fed successively from said feeder, the final unit in the series consisting of a lapper, a second hopper feeder located between said units and through which the cotton is fed from one of said units to the next, cotton feeding devices for feeding the cotton from the hopper of said first hopper feeder into the first of said picker units, variable speed mechanism for driving said cotton feeding devices, a feeler in the hopper of said second hopper feeder, connections for causing said feeler to adjust said variable speed mechanism to speed up the rate of delivery of cotton when the supply in the second hopper feeder decreases and to slow down said rate of delivery when the supply increases, and an evener mechanism for receiving the cotton from said second hopper feeder and feeding it to said lapper, said evener mechanism controlling the rate of discharge 100

120 of cotton from said second hopper feeder. 130

8. A single process picker system comprising, in combination, a hopper feeder arranged to receive cotton automatically from a distributing system, mechanism for automatically controlling the delivery of cotton to said feeder in accordance with the requirements of the feeder, a plurality of picker units in series with said hopper feeder and to which the cotton is fed successively from said feeder, the final unit in the series consisting of a lapper equipped with an automatic knock-off mechanism, a second hopper feeder located between said units and through which the cotton is fed from one of said units to the next, cotton feeding devices for feeding the cotton from the hopper of said first hopper feeder into the first of said picker units, variable speed mechanism for driving said cotton feeding devices, a feeler in the hopper of said second hopper feeder, connections for causing said feeler to adjust said variable speed mechanism to speed up the rate of delivery of cotton when the supply in the second hopper feeder decreases and to slow down said rate of delivery when the supply increases, an evener mechanism for receiving the cotton from said second hopper feeder and feeding it to said lapper, said evener mechanism controlling the rate of discharge of cotton from said second hopper feeder, and means under the control of said knock-off mechanism for automatically stopping the feed of cotton to said units and to said second hopper feeder when said lapper knocks off and for automatically starting said feed again when said lapper is started up.

9. A single process picker system comprising, in combination, a series of machines arranged to act successively and continuously on a supply of cotton to work it into the form of a lap, said machines including a lapper together with a picker of a different type and two hopper feeders arranged one in advance of the other, variable speed mechanism for driving the cotton feeding elements of said first feeder, means responsive automatically to changes in the quantity of cotton in the second hopper feeder for acting through said variable speed mechanism to control the rate of delivery of cotton from the first hopper feeder to the second hopper feeder, and an evener mechanism between said second feeder and said lapper, said evener mechanism controlling the second feeder and serving to feed cotton to said lapper.

10. A single process picker system comprising, in combination, a series of machines arranged to act successively and continuously on a supply of cotton to work it into the form of a lap, said machines including a lapper and two hopper feeders arranged one in advance of the other with a picker unit between them, variable speed mechanism for driving the cotton feeding elements of said first feeder, a feeler in the hopper of said

second feeder, connections between said feeler and said mechanism for causing said feeler to adjust said mechanism in accordance with variations in the quantity of cotton in the hopper of the second feeder, and an evener mechanism between said lapper and said second feeder, said evener mechanism controlling the second feeder and serving to feed cotton to said lapper.

11. A single process picker system comprising, in combination, a series of machines arranged to act successively and continuously on a supply of cotton to work it into the form of a lap, said machines including a lapper and two hopper feeders arranged one in front of the other, the rear hopper feeder being adapted to receive its supply of cotton from an automatic distributing system, means associated with said first feeder for automatically controlling the delivery of cotton thereto in accordance with variations in the quantity of cotton in its hopper, a variable speed mechanism for driving the first hopper feeder, a feeler in the hopper of the second feeder responsive automatically to variations in the quantity of cotton therein, connections between said feeler and said mechanism for causing said mechanism to vary the rate at which cotton will be delivered from the first feeder in accordance with variations in the quantity of cotton in the second feeder, and an evener mechanism for receiving the cotton from said second feeder and feeding it to said lapper, said evener mechanism controlling the rate of discharge of cotton from said second hopper feeder.

12. A single process picker system comprising, in combination, a series of machines arranged to act successively and continuously on a supply of cotton to work it into the form of a lap, said machines including a lapper together with a picker of a different type and two hopper feeders arranged one in advance of the other, variable speed mechanism for driving the cotton feeding elements of said first feeder, means responsive automatically to changes in the quantity of cotton in the second hopper feeder for acting through said variable speed mechanism to control the rate of delivery of cotton from the first hopper feeder to the second hopper feeder, an evener mechanism between said second feeder and said lapper, said evener mechanism controlling the second feeder and serving to feed cotton to said lapper, and means for automatically stopping the feed of cotton through said entire series of machines when said lapper knocks off and for starting said feed again when said lapper is started up.

13. In a single process picker system, the combination of a series of machines arranged to act successively and continuously on a supply of loose cotton to work it into the form of a lap, said series of machines including

a plurality of pickers, means for feeding cotton continuously from one of said machines to another, a hopper feeder located between said pickers, and means responsive to variations in the quantity of cotton in said hopper feeder for automatically controlling the rate of feed of the cotton to said hopper feeder.

14. In a single process picker system, the combination of a hopper feeder, means for feeding cotton continuously to said hopper feeder, said means including a picker, mechanism for automatically controlling said feeding means in accordance with variations in the supply of cotton in said hopper feeder, a lapper to which the cotton is fed from said hopper feeder, and an evener mechanism located between said lapper and said hopper feeder.

15. In a single process picker system, the combination of a hopper feeder, means for feeding cotton continuously toward said hopper feeder, variable speed mechanism for driving said feeding means, means for automatically controlling said variable speed mechanism in accordance with variations in the supply of cotton in said hopper feeder, a lapper to which the cotton is fed from said hopper feeder, and an evener for acting on said cotton between said lapper and said hopper feeder.

16. In a single process picker system, the combination, of a hopper feeder, a lapper, mechanism for feeding loose cotton from said hopper feeder to said lapper, said mechanism including an evener, a plurality of cotton handling units for feeding loose cotton to said hopper feeder, a variable speed mechanism for driving one of said units, and means for controlling said variable speed mechanism automatically in response to variations in the quantity of cotton in said hopper feeder.

17. In a single process picker system, the combination of a hopper feeder, a lapper, mechanism for feeding loose cotton from said hopper feeder to said lapper, said mechanism including an evener, a plurality of cotton handling units for feeding loose cotton to said hopper feeder including a second hopper feeder having a feed lattice therein, a variable speed mechanism for driving said lattice and one of the feeding units between said hopper feeders, and means for automatically controlling said variable speed mechanism in response to variations in the quantity of cotton in said first mentioned hopper feeder.

18. That improvement in processes of picking cotton and the like, which consists in subjecting the cotton to a plurality of picking operations and finally working it into the form of a lap, feeding the cotton continuously from one of said operations to the next, accumulating the cotton between certain of the picking operations, and utilizing variations

in the quantity of cotton so accumulated to so control the rate of feed of cotton at preceding points as to constantly maintain within very narrow limits the variations in the quantity of cotton at said point of accumulation. 70
